UNITED STATES PATENT OFFICE.

DANIEL S. WAUGH, OF DENVER, COLORADO, ASSIGNOR TO THE DENVER ROCK DRILL MANUFACTURING COMPANY, OF DENVER, COLORADO, A CORPORATION OF DELAWARE.

MOTOR.

1,090,179.

Specification of Letters Patent. Patented Mar. 17, 1914.

Application filed September 9, 1913. Serial No. 738,845.

To all whom it may concern:

Be it known that I, DANIEL S. WAUGH, a citizen of the United States, residing at Denver, in the county of Denver and State of Colorado, have invented new and useful Improvements in Motors, of which the following is a specification.

The present invention relates to motors operated by fluid under pressure, and while primarily intended for use in connection with rock drilling machinery, it is not necessarily limited to such operations.

As is well known to those skilled in the art, there is a great advantage in employing a short stroke and securing a comparatively light blow when first starting to drill a hole in a rock, and there is the same advantage when drilling through what is termed "bad ground," namely, rock which is full of seams and fissures, for in the latter case, the drill bit is more apt to stick and stop the machine if a long stroke with a consequent hard blow is struck. After a hole is started, however, and under ordinary conditions, the long stroke is desirable.

Now, the primary object of the present invention is to provide novel, simple and effective means, whereby the stroke of the machine can be varied, the throttle valve, which controls the supply of motive fluid to the motor being employed as the controlling means for varying the stroke.

A simple embodiment of the invention that has been found in use to be entirely practicable and satisfactory, is illustrated in the accompanying drawings, wherein:—

Figure 1 is a longitudinal sectional view through a portion of a motor containing the improvements. Fig. 2 is a cross sectional view of the same. Fig. 3 is a horizontal sectional view on the line 3—3 of Fig. 1. Figs. 4 and 5 are detail sectional views, illustrating the throttle valve in its different controlling positions to vary the stroke of the piston. Fig. 6 is a view that is diagrammatic in its character, showing various of the passages and ports disposed in substantially the same plane in order to more fully disclose the operation of the mechanism. Fig. 7 is a sectional view on the line 7—7 of Fig. 1. Fig. 8 is a detail perspective view of the distributing valve and part of the elements associated therewith.

Similar reference numerals designate corresponding parts in all the figures of the drawings.

In the embodiment disclosed, a cylinder member 9 is employed, which contains a reciprocating piston 10 having a reduced extension 11 at one end, and being bored out to receive the usual rifle bar 12 that engages a nut 13 carried by the piston and arranged within the same.

Mounted longitudinally upon the cylinder member 9, and preferably forming an integral part of the same, is a longitudinally disposed distributing valve casing 14, which is provided with an open-ended internal chamber having a central internal annular groove 15 and other similar grooves 16 and 17 arranged on opposite sides thereof. A motive fluid supply passageway 18 leads to the central groove 15, and is controlled by a tapered throttle valve 19 journaled transversely in the cylinder member between the piston chamber and the valve casing. This valve 19 has a stem 20 projecting from one side of the cylinder member, and the projecting portion carries a handle 21 provided with a series of depressions 22 arranged to receive a spring-pressed holding plunger 23. The tapered portion 19 of the valve is provided with a port 24 opening through its larger end and through one side, the side opening affording communication with the passageway 18, as will be clear by reference to Fig. 2. Threaded into the side of the cylinder member, opposite the projecting stem 20, and in line with the open end of the valve 19, is a coupling 25 comprising a pair of telescoping socket elements 26 detachably threaded together and inclosing the ball end 27 of a motive fluid supply connection 28. It will thus be seen by reference to Figs. 1, 2 and 6, that the valve may be turned either to a position to admit motive fluid from the supply conduit 28 to the central groove 15 of the valve casing, or to a position to cut off such communication.

Leading from the two annular grooves 16 of the valve casing, are distributing passageways 29 and 30 that respectively open into the rear and front portions of the cylinder member. Detachably fitted in the opposite end portions of the distributing valve chamber, are bushings 31 having flanges 32 that

bear against the ends of the casing. These bushings are provided with internal annular grooves 33 that communicate respectively with the grooves 16, and consequently with the passageways 29 and 30, as illustrated at 34. Their inner or adjacent ends are slightly spaced apart to afford open communication with the annular groove 15. An automatic reciprocatory distributing valve 35 is mounted in these bushings, and has a central peripheral enlargement 36 that is arranged to slidably contact with the inner end portions of the bushings and bridge the spaces between them. It is also provided at its ends with enlargements 37 that slidably engage the bore walls of said bushings. The valve is preferably hollowed out from its ends, as illustrated at 38. Flanged caps 39 close the outer ends of the bushings and are held in place by cross heads 40, bearing thereagainst and secured by bolts 41, which extend longitudinally through the valve casing on opposite sides of the valve chamber. The exhaust from the motor takes place through comparatively large outlet ports 42 in communication with each other, as shown at 43, and also in communication with the end grooves 17 of the valve chamber. These end grooves 17 are in turn in communication with the interiors of the bushings 31 through openings or ports 44 bored therethrough. With this structure, it will be evident that if the distributing valve 35 is in its right hand position, as illustrated in Fig. 1, motive fluid under pressure, passing through the open throttle valve 19, will enter the groove 15, and passing between the inner ends of the bushings 31, it will be directed to the rear groove 16, and thence entering the passageway 29, will be delivered into the rear end of the cylinder member, moving the piston forward. The fluid in advance of the piston will exhaust through the passageway 30, the grooves 16, the communicating ports 34, and thence through the ports 44 and foremost groove 17, finally exhausting through the ports 42. The movement of the distributing valve 35 to its rearmost position will reverse the operation, the motive fluid then entering the passageway 30 and driving the piston rearwardly, whereupon the motive fluid in rear of said piston will exhaust through the passageway 29 and the rearmost ports 44, escaping in like manner through the ports 42.

The means for effecting the operation of the distributing valve is as follows. A passageway 45 is bored longitudinally in the cylinder member and opens through a port 46, into the front portion thereof, normally in advance of the piston 10. This passageway, as shown at 47, in Fig. 7, leads to the rear end of the valve chamber, where it communicates with an annular groove 48, formed in the rear cap 39. This groove has

communication through ports 49 with a bore 50 in the cap, so that if there is motive fluid under pressure in the front portion of the cylinder member, when the piston moves rearwardly and uncovers the port 46, this motive fluid will pass through said port 46, the passageway 45, the passage 47, into the rear end of the distributing valve chamber, and operating against the rear face of the valve 35, will force it forward. As already explained, this will result in fluid under pressure being delivered through the passageway 29 into the rear portion of the cylinder member, thereby driving the piston forward. Now there is provided, as illustrated particularly in Fig. 6, another passageway 51 that opens through ports 52 in the front cap 39 into the front end of the distributing valve chamber, and this passageway 51 has communication with the rear portion of the cylinder member through two ports 53 and 54, one being arranged in advance of the other. The piston successively uncovers these ports. The communication between the rear port 53 and the passageway 51 is established through the medium of the bore in which the throttle valve 19 operates, or in other words, the rear end of the passageway 51 and the outer end of the port 53 open into said bore, as will be clear by reference to Fig. 6. The valve 19, if constructed in the ordinary manner, would thus cut off all communication between the ports 53 and 51, but it is provided with a cut-away portion 55, this cut-away portion being of sufficient length so that when the valve 19 is in one position, as illustrated in Figs. 5 and 6, it permits communication between the port 53 and the passageway. When, however, the valve 19 is fully opened, as illustrated in Fig. 4, then communication between the said port 53 and the said passageway 51 is cut off.

Referring more especially to Fig. 6, the operation of this portion of the mechanism is as follows. When the machine is initially started for the purpose of beginning a drill-hole, the throttle valve 19 is thrown to the position illustrated in Figs. 5 and 6, and this position will be indicated as will be apparent by the plunger 23 engaging in the proper recess 22 in the handle 21. It will thus be obvious that upon the forward stroke of the piston, as soon as said piston uncovers the port 53, motive fluid under pressure will pass through said port, through the cut-away portion 55, entering the passageway 51, and thus being admitted against the front end of the distributing valve, the valve will immediately be shifted to its rearmost position, whereupon the piston will start on its rear stroke. If, however, the throttle valve 19 is thrown fully open, then the port 53 will be cut off from communication with the passageway 51, and

the piston must travel until the port 54 is uncovered before a reversal takes place.

From the foregoing, it is thought that the construction, operation, and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In a motor of the character described, the combination with a cylinder member and a piston operating therein, of means for supplying fluid under pressure to the motor, an automatic shiftable distributing valve for the motor, means for changing the period of operation of the distributing valve to vary the stroke of the piston, and a throttle valve controlling the motive fluid supply to the motor and the means for changing the period of operation of the valve.

2. In a motor of the character described, the combination with a cylinder member and a piston operating therein, of means for supplying fluid under pressure to the motor, an automatic shiftable distributing valve for the motor, means for changing the period of operation of the distributing valve to vary the stroke of the piston, including a plurality of ports for supplying motive fluid to the distributing valve, and common means for controlling the motive fluid supply to the motor and for controlling one of said ports.

3. In a motor of the character described, the combination with a cylinder member and a piston operating therein, of means for supplying fluid under pressure to the motor, an automatic shiftable distributing valve for the motor, means for changing the period of operation of the distributing valve to vary the stroke of the piston, including a plurality of ports for supplying motive fluid to the distributing valve, and a single valve for controlling the motive fluid supply to the motor and for controlling one of said ports.

4. In a motor of the character described, the combination with a cylinder member and a piston operating therein, of means for supplying fluid under pressure to the motor, an automatic shiftable distributing valve for the motor, means for changing the period of operation of the distributing valve to vary the stroke of the piston, including a plurality of ports for supplying motive fluid to the distributing valve, and a single rotary throttle valve disposed transversely of the cylinder member and controlling the

motive fluid supply to the motor and the passage of motive fluid through one of the ports.

5. In a motor of the character described, the combination with a cylinder member and a piston operating therein, of means for supplying motive fluid to the motor, an automatic distributing valve, means for effecting the shifting of the valve, including a plurality of ports covered and uncovered by the piston on its movement, and a throttle valve controlling the motive fluid supply to the motor and one of the ports.

6. In a motor of the character described, the combination with a cylinder member and a piston operating therein, of means for supplying motive fluid to the motor, an automatic distributing valve, means for effecting the shifting of the valve in one direction, including a plurality of ports opening into the cylinder member and successively covered and uncovered by the piston on its movement, and a throttle valve controlling the motive fluid supply and having a portion that is movable to and from a position to cover one of the ports.

7. In a motor of the character described, the combination with a cylinder member and a reciprocating piston operating therein, of a valve casing, a motive fluid supply passage leading to the valve casing, and distributing passages leading from said valve casing to the cylinder member, an automatic distributing valve in the valve casing, means for effecting the shifting of the valve including a plurality of ports opening into the cylinder member and successively covered and uncovered by the piston in its movement, and a rotary throttle valve controlling the motive fluid supply passage and one of the ports.

8. In a motor of the character described, the combination with a cylinder member and a reciprocating piston operating therein, of a valve casing mounted on the cylinder member, a motive fluid supply passage leading to the valve casing, distributing passages leading from the valve casing to the cylinder member, an automatic distributing valve in the valve casing, means for shifting the automatic valve in one direction, comprising a passageway leading from the cylinder member to the valve casing and having a plurality of ports opening into the cylinder member and successively covered and uncovered by the piston, and a rotary hollow throttle valve located in the supply passage and controlling the same, said valve having a portion movable across one of the ports to open and close said port.

9. In a motor of the character described, the combination with a cylinder member and a piston operating therein, of means for supplying motive fluid to the motor, means for varying the stroke of the piston, and a

- throttle valve disposed transversely of the cylinder member and controlling the motive fluid supply and the piston stroke varying means.
- 5 10. In a motor of the character described, the combination with a cylinder member and a piston operating therein, of means for supplying motive fluid to the motor, means for varying the stroke of the piston, and a 10 rotatable throttle valve journaled in the cylinder member transversely thereof and controlling the motive fluid supply and the piston stroke-varying means.
11. In a motor of the character described, 15 the combination with a cylinder member and a piston operating therein, of means for supplying motive fluid to the motor, including a supply passageway, means for varying the stroke of the piston, including a motive fluid passageway, and a valve for controlling both passageways, said valve automatically moving toward a closed position across one passageway when moving to an open position with respect to the other.
- 25 12. In a motor of the character described, the combination with a cylinder member and a piston operating therein, of means for supplying motive fluid to the motor, including a supply passageway, means for varying the 30 stroke of the piston, including a motive fluid passageway, and a single valve journaled transversely of the cylinder member and movable across both passageways, said valve automatically moving toward a closed position 35 across the motive fluid supply passageway when moving to an open position with respect to the stroke varying passageway.
13. In a motor of the character described, 40 the combination with a cylinder member, of a piston operating therein, an open-ended valve casing having distributing ports communicating with the cylinder member, shiftable bushings extending into the valve casing from its opposite ends and terminating 45 short of each other, a reciprocating distributing valve operating in the bushings, means for introducing motive fluid between the inner ends of the bushings, and caps
- mounted over the outer ends of said bushings.
14. In a motor of the character described, 50 the combination with a cylinder member, of a piston therein, a valve casing having distributing ports communicating with the cylinder member, bushings in the valve casing 55 terminating short of each other and having bores communicating with the distributing ports, means for introducing motive fluid between the bushings, and an automatic distributing valve operating in the bushings 60 and having a peripheral enlargement between its ends that moves across the space between the bushings and alternately enters their adjacent ends to alternately admit the motive fluid to and cut it off from each bushing.
15. In a motor of the character described, 65 the combination with a cylinder member, of a piston therein, a valve casing that distributing ports communicating with the cylinder member, bushings in the valve casing 70 terminating short of each other and having bores communicating with the distributing ports, the inner ends of said bores being enlarged, means for introducing motive fluid 75 between the bushings, and an automatic distributing valve operating in the bushings and having peripheral enlargements at its ends that reciprocate in the outer portions of the bushing bores, said valve 80 having a central peripheral enlargement of greater diameter than the end enlargements and said central enlargement moving across the space between the bushings and alternately entering the enlarged 85 portions of the bores thereof to alternately admit the motive fluid to and cut it off from said bushings.
- In testimony whereof I have hereunto set my hand in presence of two subscribing witnesses.
